MOLD FOR FIBER PULP AND THE LIKE

Francis S. Farley, Trenton, N. J., assignor to
 Daniel Manson Sutherland, Jr., Morrisville,
 Pa.

Application May 7, 1930. Serial No. 450,539

14 Claims. (Cl. 92—61)

My invention relates to molds for fiber pulp and the like, such as are used in the manufacture of fiber board, and is more especially concerned with the filling or charging of such molds with pulp and with the draining off of the water from the pulp to leave the fibers behind in the form of "raw" board. As regards charging, I aim to provide for the free escape of air from the mold without permitting any substantial escape or loss of pulp; while as regards drainage, I aim to provide free escape for the water from the pulp after the mold is fully charged, while preventing any premature escape,—which might interfere with uniform charging and result in defective or 15 unhomogeneous board.

How these and other advantages can be realized through the invention will appear from my description hereinafter of selected and preferred forms of air vent and water-lock arrangements.

20 In the drawings, Fig. I shows a vertical section through a portion of a mold equipped with a convenient form of apparatus for the purposes of my invention.

Fig. II shows a horizontal section through the 25 apparatus, taken as indicated by the line and arrows II—II in Fig. I.

Fig. IIa is a detail sectional view, likewise taken as indicated by the arrows II—II in Fig. I, drawn to the same scale as the latter illustration, and more limited in scope than Fig. II.

Fig. III is a fragmentary cross section taken as indicated by the arrows III—III in Figs. I and II.

Fig. IV is a view similar to Fig. I illustrating 30 a somewhat different form of apparatus for venting the air from the mold.

Fig. V is a view similar to Fig. IV, showing the parts in different positions.

Fig. VI shows a horizontal section taken as indicated by the line and arrows VI—VI in Fig. IV.

Fig. VII is a plan view of the apparatus of Figs. IV to VI.

Fig. VIII is a view similar to Fig. I, illustrating 45 a somewhat different form of apparatus for draining the pulp from the water in the mold.

Fig. IX is a view at right angles to Fig. VIII, partly in elevation and partly in vertical section, as indicated by the line and arrows IX—IX in Fig. VIII, showing the parts in different positions.

Fig. X shows a horizontal section taken as indicated by the line and arrows X—X in Fig. VIII.

In Fig. I of the drawings are shown the principal parts of a mold for forming "raw" sheets of fiber pulp, which sheets may afterward be compacted and dried into fiber board useful for

building, for thermal insulation or sound insulation, or for other purposes.

As here shown, the mold comprises a bed or bottom 10, a top 11 and a marginal wall or "deckle" 12. The top 11, which is shown suspended by links 13, can be adjusted up or down to vary the vertical dimension and capacity of the mold cavity 15, so as to control the thickness of the fiber board ultimately produced. It can be lowered or depressed to squeeze the water out of the pulp and bring the fibers together into a more or less cohesive sheet, and can also be raised to permit removal of this sheet. The deckle 12 can likewise be raised to open up the mold for removal of the formed raw sheet.

Tightness of the joints is provided for by packings 16, 17 on the margin of the bed 10 and the lower edge of the deckle 12, and by packing 18 on the lower corners of the top 11. As shown,

the packing 18 bears against plates 19 in which the air vent ports are cut. An air outlet 20 is shown in the deckle 12 to permit free egress of air from the mold cavity 15 while the latter is being charged with pulp which enters through

gate controlled ports 15a at opposite sides of the mold from hoppers 15b, see Figs. II and III. A drainage outlet for water squeezed out of the pulp by depression of the mold top 11 is afforded by channels 21 leading to a discharge

passage in a header 22 secured to the edge of the bed. A pervious mold bottom consisting of a perforated plate 23 over the channels 21 prevents the pulp fibers from getting into the channels 21 and clogging them up, while allowing

free passage of the water. As shown, there is an unperforated marginal extension of the cover plate or sheet 23 over the otherwise open top of the header 22, secured to its outer edge. Wires 25 are shown on top of the plate 23, adapted to serve as a travelling belt to carry away the

pulp sheet after the mold has been opened up. While the mold is closed, these wires 25 lie embedded in the corresponding packings (not shown).

As shown in Fig. I, the air outlet 20 leads to a cylindrical air discharge and liquid drainage chamber 26 mounted on the deckle 12. This chamber 26 is freely vented to the atmosphere through a grating 27 across its otherwise open

top. The vertical dimension of the outlet 20 where it opens through the deckle 12 is such as to cover the full range of vertical adjustments of the mold top 11, so as always to afford an air outlet from the upper region of the mold cavity 15. A barrier 28 affords an overflow for

liquid from the outlet 20 at a height slightly above the highest adjusted position of the mold top 11, so that no pulp can escape through the outlet 20 until the mold cavity 15 is completely filled. As here shown, the barrier 28 is defined by the lower edge of a port 29 in a drainage connection cylinder 30 extending up into the chamber 26, which cylinder 30 in the present instance forms or closes the bottom of the air discharge and liquid drainage chamber at 26. A packing 30x in the lower part of the chamber 26 assures tight joints. An opening 31 in the top of the cylinder 30 allows free discharge of air into the open-topped chamber 26, and a pipe 32 connected into the bottom of the cylinder affords a discharge for liquid (pulp or water) to any convenient point.

As here shown, there is a curved pipe connection 33 from the water discharge outlets 21 and header 22, leading downward and then up through the bottom of the cylinder 30, with an upright extension 34 within the cylinder. From the pipe 34 there is an overflow 35 into the interior of the cylinder 30, defined by the lower edge of a port 36 in the upstanding pipe 34. The bottom edge 35 of the port 36 is just below the level of the lower side of the perforated plate 23. Port 36 and the overflow at 35 are controlled by a valve sleeve 37 around the pipe 34, provided with ports 38 and 39. The valve 37 is connected to the top mold 11 by a cable 40, extending over pulleys 41, and provided with a turnbuckle 42 as a means of adjustment. A helical compression spring 43 may be provided between the top of the cylinder 30 and a flange 44 on the valve 37, to reinforce gravity in depressing the valve. The valve 37 has guide slots 45 for pins 46 on the pipe 34, to insure proper correspondence of the ports 36, 38. The upper ends of pipe 34 and valve sleeve 37 are open, to permit free venting of air,—or even overflow of liquid, in case of need. As shown, there is a connection between the pipes 33 and 32, controlled by a valve 47, so that the water from the header 22 can be drained off directly.

The operation of the air-vent and water-lock arrangements shown in Figs. I-IV is as follows:

The mold top 11 having been adjusted to the proper height for the ultimate board thickness desired, the mold is charged with pulp admitted through ports 15a in the end walls (Figs. II and III) of the mold. As the pulp enters, the air escapes at 20, passing through the port 29 and the opening 31 to the upper part of the air discharge chamber 26 and its grated opening at 27 to the atmosphere, and some of the pulp enters the outlet 20 and may even overflow at 28 into the lower end of the cylinder 30.

The mold top 11 is now lowered or depressed, thus forcing the water from the pulp out through the holes in the plate 23 and the subjacent channels 21 into the header 22, and thence down and up into the pipe 34. As the mold top 11 descends, the valve 37 necessarily rises, and the port 38 in the valve comes over the port 36 in the pipe 34, so that the water in the pipe 34 overflows at 35 and escapes into the cylinder 30 in the air discharge and liquid drainage chamber 26, and through the pipe 32. At the end of its movement, the mold top 11 overtravels the lower edge of the outlet 20, thus sealing off the latter from the mold cavity 15.

When the fiber pulp has been sufficiently squeezed and compacted in the mold cavity 15, the deckle 12 is raised, carrying with it the cham-

ber 26. The cylinder 30, being fixed to the base 10, remains stationary, and thus in effect slides out of the chamber 26, virtually lowering the barrier 28 so that the pulp trapped in the outlet 20 has a chance to overflow into the cylinder 30 and escape through the pipe 32. Then the mold top 11 is raised, and the fiber sheet that has been formed is loosened from the mold top and allowed to fall on the conveyor wires 25, which are put in motion to carry the sheet out of the mold on its way to the next stage of treatment. Thereupon the parts may be returned to their positions shown in Fig. I, and the mold may be recharged with pulp, etc., as before.

It will be understood that in practice the whole structure shown in Fig. I may be duplicated at the other side or end of the mold cavity 15, to afford a freer and more uniform discharge for air and water.

Figs. IV, V, VI and VII illustrated a water-lock arrangement similar to that of Figs. I and II, but without the air-vent features. Here the liquid drainage chamber 26a is attached directly to the pipe 33a from the header 22, so that water from the header 22 enters the annular space in the chamber 26a around the upright pipe 34a and ultimately overflows into the pipe 34a over the lower edge 35a of the port 36a in said pipe 34a, which is connected directly to the discharge pipe 32a. The cylinder 30 of Figs. I and II is omitted altogether.

Other parts and features are marked with the same reference characters as in Figs. I and II, as a means of dispensing with merely repetitive description.

In Fig. IV, the mold top 11 is shown in its lowermost position, with a fully formed pulp sheet 15a between it and the foraminous member 23, and with the ports 36a, 38a open to permit overflow of water from the chamber 26a into the outlet pipe 34a. In Fig. V, the valve sleeve 37a is shown in its lowermost position, with the port 36a closed. The operation is the same as described above in reference to the water-lock features of Figs. I and II.

In Figs. VIII, IX and X is shown an air vent arrangement similar to that of Figs. I and II, but without the waterlock features. Here the air discharge chamber 26b and its central upstanding pipe 30b correspond to the chamber 26 of Figs. I and II, and the vertical drain pipe 30b corresponds to the drainage cylinder 30 of Figs. I and II,—being connected to the discharge 32b. As shown, the lower end of the chamber 26b is provided with a stuffing box 51 through which the pipe 30b slides. The pipe 30b has a port 29b corresponding to the port 29 in Figs. I and II, and the pipe 50b has a port 52b adapted to overlap the port 29b when the chamber 26b rises with the deckle 12, thus allowing complete discharge of pulp from the chamber 26b and the outlet 20. As herein shown, the outlet 20 has a lateral clean-out opening normally closed by a detachable cover plate 20b. A flexible water connection 53b is shown to the upper end of the chamber 26b, as a means of washing out dried pulp that might possibly collect therein under the grating 27. The chamber 26b is further fitted at the bottom with a valve 54b for draining off the wash water subsequently.

Various parts and features here shown are marked with the same reference characters as in Figs. I and II, as a means of dispensing with repetitive description. The operation of the device is the same as above described in connection

with the air vent features shown in Figs. I. and II.

Having thus described my invention, I claim:

1. The combination with a fiber pulp mold having a water drainage outlet and an air vent outlet, a top depressible to squeeze out the water, and a part movable up and down to open the mold for removal of the formed product and to close it for charging with pulp, of means for controlling said water drainage outlet actuated by the up and down movement of said top, and means for controlling drainage from said air vent outlet actuated by the up and down movement of said part.

2. The combination with a fiber pulp mold having a water drainage outlet and an air vent outlet, a top depressible to squeeze out the water, and a part movable up and down to open the mold for removal of the formed product and to close it for charging with pulp, of a chamber connected with said part to move up and down therewith and vented to the atmosphere above the top of the mold cavity, a connection sliding out of and into said chamber as the chamber moves up and down, and thereby opened to drain off water from said air vent and closed to permit charging of the chamber with pulp, a drain pipe upstanding in said chamber with an overflow opening below the level of said water drainage outlet, a valve sleeve cooperating with said pipe, and means actuated by said mold top to raise and lower said sleeve and thereby open and close said overflow opening.

3. The combination with a fiber pulp mold having a movable wall and a controllable water drainage outlet, of means controlled by movement of said wall for closing said outlet while the mold is being charged with pulp and for opening it to permit the water from the pulp to drain away.

4. The combination with a fiber pulp mold having a water drainage outlet and a top depressible to squeeze out the water, of means actuated by the movements of said top to open and close said outlet.

5. The combination with a fiber pulp mold having a water drainage outlet, of automatic valve means for shutting off said outlet from the mold cavity while the mold is being charged with pulp, and an overflow into said outlet above the top of the mold cavity.

6. The combination with a fiber pulp mold having a water drainage outlet directly from its cavity, of a drainage chamber with connection to said outlet extending to a lower level, an overflow at a level intermediate said lower level and that of said outlet, and another overflow from said chamber at a level above the top of the mold cavity.

7. The combination with a fiber pulp mold having a water drainage outlet directly from its cavity, of a drainage chamber with connection to said outlet extending to a lower level, an overflow at a level intermediate said lower level and

that of said outlet, and automatic valve means for closing said overflow while the mold is being charged with pulp.

8. The combination with a fiber pulp mold having a water drainage outlet directly from its cavity, of a drainage chamber with connection to said outlet extending to a lower level, an overflow at a level intermediate said lower level and that of said outlet, and means for automatically limiting overflow to a level above the top of the mold cavity while the latter is being charged with pulp.

9. The combination with a fiber pulp mold having a water drainage outlet directly from its cavity and a top depressible to squeeze out the water, of a drainage chamber connected to said outlet, a drain pipe upstanding in said chamber with an overflow opening below the level of said outlet, a valve sleeve cooperating with said pipe, and means for raising and lowering said valve sleeve as said mold top is depressed and raised, so as to open and close said overflow opening.

10. The combination with a fiber pulp mold having an outlet from the upper region of the mold cavity, of a discharge overflow from said outlet at a level above the top of the mold cavity, and an air vent from a still higher level.

11. The combination with a fiber pulp mold having an outlet from the upper region of the mold cavity, of a chamber communicating with said outlet and vented to the atmosphere, and a discharge overflow from said chamber at a level above the top of the mold cavity.

12. The combination with a fiber pulp mold having an outlet from the upper region of the mold cavity, of a chamber connected to said outlet and vented to the atmosphere at a level above the top of the mold cavity, and means for opening a drainage connection from said outlet through said chamber when the mold is opened.

13. The combination with a fiber pulp mold having a part movable up and down to open the mold for removal of the formed product and to close it for charging with pulp, of a chamber connected with said part to move up and down with it and also communicating with the upper region of the mold cavity and vented to the atmosphere at a higher level, and a drainage connection opened and closed by the up and down movement of the chamber.

14. The combination with a fiber pulp mold having a part movable up and down to open the mold for removal of the formed product and to close it for charging with pulp, of a chamber mounted on said part communicating with the upper region of the mold cavity and vented to the atmosphere at a higher level, and a drainage connection sliding out of and into said chamber as the chamber moves up and down, and thereby opened and closed.

FRANCIS S. FARLEY.
